UNITED STATES PATENT OFFICE

FRITZ KUHENNE, OF OESTERAU IN WESTFALEN, GERMANY, ASSIGNOR TO THE FIRM
BROCKHAUS SOHNE, OF WESTFALEN, GERMANY

VISE

Application filed April 18, 1931, Serial No. 531,218, and in Germany October 21, 1929.

This invention relates to improvements in vises and more particularly to vises of the kind permitting rotation of the vise by means of a support which is rotatably mounted upon a hollow base adapted to be fixed to the work-table and having a lever for locking the vise in any angular position which may be given thereto by rotation.

The principal object of my invention is to 10 devise a construction of a vise permitting it to fully maintain its rotary character and to lock and unlock the vise in any desired angular position solely by a short rotation of said lever.

15 According to my invention I provide oblique surfaces at the under surface of the upper wall of the base, said oblique surfaces co-operating with the hand lever which preferably is likewise provided with oblique 20 surfaces similar to said former surfaces. This lever according to my invention is swingably mounted upon a stud extending from the under part of the vise into the base and passing through the wall of the 25 latter. Locking of the vise in any desired angular position is effected by said lever which after being properly rotated only a short distance will be pressed on the one hand against the oblique surfaces at the upper 30 wall of the base and on the other hand against an abutment which is provided at said stud.

Known constructions of rotatable vises had ordinarily been provided with locking 35 means in the form of oblique surfaces at the under part of the vise and with a lever having similar oblique surfaces co-operating with said former surfaces. In known constructions of rotatable vises, however, the 40 entire weight of the vise together with the work piece held therein had to be supported by said oblique surfaces. In consequence of the considerable strain ordinarily imposed upon said oblique surfaces the latter had 45 been subject to considerable wear and actuation of the lever had been difficult, because during locking the vise by said lever it had been necessary to always lift the entire 50 weight of the vise and of the work piece held therein. Furthermore, in known construc-

tions of this kind, when locking or unlocking the vise by means of the lever, the vise had to be kept in position by hand, because otherwise the vise would be liable to rotate together with the lever during rotation of the latter.

The vise constructed according to my present invention is free from this drawback and the locking means which comprise the aforementioned oblique surfaces will be fully released from any strains due to the weight of the vise and the work pieces held therein. According to my invention the under part of the vise during locking the latter in any desired angular position is drawn downward 65 towards the base and firmly connected therewith by the action of jamming.

Threaded nuts in conjunction with hand levers which had heretofore been used for drawing downward the under part of the 70 vise towards the base are entirely unsuitable for solving the problems underlying my present invention, because, in the first place, said threaded nuts and levers do not warrant the possibility of free rotation of the vise and, in the second place, they do not permit locking the vise in every angular position merely by a short rotation of a hand lever as is the case in the construction forming part of my 75 present invention.

80 A further object of my invention consists in devising a locking mechanism for rotatable vises which permits locking of the vise in any desired angular position, said locking mechanism being constructed especially with a view of attaining easy adjustment and, if necessary, easy replacement and interchangeability of all parts of the locking mechanism which are subject to wear. For this purpose according to my invention the 85 stud which is fast on the under part and extends through the wall of the base thereof is constructed in the form of a threaded bolt, while the collar which is provided on said stud forms an abutment for said lever, said 90 collar consisting of a threaded nut or a further washer or plate adjacent to said nut.

95 In order to prevent any undesirable unlocking of the vise due to hammer blows or other vibrations, according to my invention 100

I further provide means which automatically secure the hand lever in locked condition of the vise against rotation and which at the same time will automatically release said lever while being rotated into unlocking position. For this purpose said lever is made slightly resilient or yielding and constructed to co-operate with a number of stops or corrugations provided at the base of the vise.

10 My invention will be more fully understood by reference to the accompanying drawings in which I have represented some forms of construction of a rotatable vise and the novel locking mechanism forming part 15 of my invention. Fig. 1 is a side-view of my new vise partly in section, Fig. 2 a plan-view corresponding to Fig. 1, Fig. 3 a side-view of a modified form of a vise partly in section and Figs. 4, 5, 6 and 7 show the particular construction of the hand lever permitting automatic locking and unlocking of said lever and therewith of the vise as a whole. Fig. 4 is a plan view of the lever, Fig. 5 a section through the stop in said lever, Fig. 6 a side- 25 view of the under part of a vise and Fig. 7 a section through the eye of said lever.

In the drawings I show a parallel vise of any of the ordinary constructions comprising an under member 4 which represents the fixed 30 jaw as well as an upper member or adjustable jaw 5, sliding on said member 4 and resting with its under part 9 rotatable on the base 1 which may be fastened to the work table at the flanges 2 by means of screws.

35 Instead of this mode of fastening, however, the vise may also be fastened to the work table by means of an adjustable clamping device. The base 1 is made in the form of an inverted cup or plate, thus forming a flat hollow space and the wall of said cup or plate is recessed at about one third of its circumference. This recessed part of the wall of the base 1 permits passage of the lever 7 while being rotated. The lever 7 is mounted rotatably within the hollow space of the base 1 around a stud or bolt 3. This stud or bolt 3 is screwed home in the under part 9 of the under member or fixed jaw 4 and extends through a central bore in the base 1 into the 40 interior hollow space thereof. The stud or bolt 3, furthermore, carries the lever 7 by means of a collar provided at the end of said stud or bolt. The under surface of the wall of the base 1 is made oblique as indicated at 45 6 and preferably the hand lever 7 is likewise provided at the point 8 thereof with oblique surfaces as shown particularly in Figs. 4 and 7, while said lever at the place 8 is of plane conformation according to Figs. 1, 2 and 3 50 60 in order to simplify the construction.

In the modified construction of the locking mechanism shown in Fig. 3 the stud or bolt 3' which forms the axle or pivot for rotation of the vise and of the lever 7 is fastened by forging or welding to the under part

9 of the fixed member or jaw 4 of the vise and provided with a thread and a nut 3'' which by the intermediary of a washer shown in Fig. 3 forms the abutment for the lever 7, whenever the surfaces 8 of said lever are in the condition of exerting a pressure upon the oblique surfaces 6 at the base 1.

The operation of the aforescribed constructions is as follows: In unlocked condition of the lever 7 and therewith of the vise, as shown in Fig. 2, the oblique surfaces 8 on said lever do not firmly press against the oblique surfaces 6 on the base 1 with the result that the vice which consists essentially of the members 4 and 5 may be rotated on the base 1 and adjusted to any desired angle with respect thereto.

If it is desired to lock the vise in a desired angular position the lever 7 is rotated, whereupon the oblique surfaces 8 on said lever will be pressed against the oblique surfaces 6, thus drawing the vise downward and pressing the under part 9 of its member 4 against the upper surface of the base. For this purpose as well as for unlocking the vise in every angular position only a slight rotation of the lever 7 will be sufficient.

According to Figs. 4, 5, 6, and 7 the lever 7 which rotates around the stud or bolt 3 and which is made adjustable by means of the collar 12 and the threaded nut 3'' is provided on its surface with corrugations or steps 10 or the like.

The under side of the upper wall of the base 1 is provided within the range of the swinging motion of the lever 7 with stops 11 of a form in agreement with said corrugations 10. The corrugations 10 will automatically engage with the one or the other of the stops 11 in every position of the lever, thus securing said lever against unintended rotation. During gripping the lever, which is somewhat resilient, with the hand, for the purpose of unlocking the vise, the lever is pressed somewhat downward which will effect unlocking of the vise.

While I have herein disclosed the invention as embodied in a vise, which affords a particularly valuable application thereof, it is obvious that the invention is applicable also to other tools or instruments, which may advantageously be mounted on a support in such a way as to be capable of being turned and clamped at will. The term "tool" employed in certain of the claims is therefore to be interpreted broadly to cover all such devices, inasmuch as the invention resides in the nature of the securing means rather than in the specific instrumentality which is secured thereby.

I claim:

1. A vise, comprising a hollow base, an under member rotatably mounted upon said base, a hand lever for locking said under member, a bolt passing through the wall of

said base and positioned intermediate the under part of said vise and said base permitting swinging of said lever around said bolt, and an oblique surface at the under part of the upper wall of said base, said oblique surface being co-operative with said lever.

2. A vise, comprising a hollow base, an under member rotatably mounted upon said base, a hand lever for locking said under member, a bolt passing through the wall of said base and positioned intermediate the under part of said vise and said base permitting swinging of said lever around said bolt, oblique surfaces at the under surface of the upper wall of said base, and further oblique surfaces on said hand lever adapted to co-operate with said former oblique surfaces.

3. A vise as specified by claim 1, in which the bolt is provided with a thread, said bolt being associated with a collar adapted to form an abutment for the lever, said collar consisting of a threaded nut co-operative with said bolt.

25 4. A vise as specified by claim 1, in which the bolt is provided with a thread, said bolt being associated with a collar adapted to form an abutment for the lever, said collar consisting of a threaded nut co-operative with said bolt and a washer positioned on said threaded nut.

5. A vise as specified by claim 1, in which the hand lever is made slightly resilient and provided with locking means permitting automatic locking and unlocking of said hand lever and therewith of said vise in a desired angular position, and corrugations provided at the base of the vise, said corrugations being adapted to co-operate with said lever.

40 6. A securing means for a tool, comprising a base upon one surface of which the tool is adapted to be seated, having an aperture therein, a stem secured to the tool and extending through the said aperture, a lever having an aperture near one end, loosely fitting on the said stem, the said base having inclined portions on its opposite surface around the aperture, the lever having corresponding inclined portions adapted to engage those of the base, and a retaining member at such position on the stem beyond the lever that the stem is free to rotate in the base when the lever is positioned to cause the cooperating inclined portions to be disengaged, but that the said stem will be locked securely to the base when the lever is positioned to cause the said portions to become firmly engaged with one another, by the resulting wedging action.

60 7. A securing means for a tool, comprising a base upon one surface of which the tool is adapted to be seated, having an aperture therein, a stem secured to the tool and extending through the said aperture, the said stem being provided with screw threads, a

lever having an aperture near one end, loosely fitting on the said stem, a nut engaging the said screw threads beyond said lever and thus preventing the lever from coming off of the stem, the said base having inclined portions on its opposite surface around the aperture, the lever having corresponding inclined portions adapted to engage those of the base, and the nut being screwed up on the stem to such position that the stem is free to rotate in the base when the lever is positioned to cause the cooperating inclined portions to be disengaged, but that the said stem will be locked securely to the base when the lever is positioned to cause the said portions to become firmly engaged with one another, by the resulting wedging action.

In testimony whereof I affix my signature.
